ABSTRACT: A method of recovering hydrocarbons from a subterranean formation having an unconsolidated or friable structure and traversed by a well bore by heating the formation to a temperature sufficient to cause incipient fusion and consolidation of the sand adjacent the well bore.

Patented Aug. 4, 1970

3,522,845

U.S. PATENT 3,522,845
**METHOD OF CONSOLIDATING AND PRODUCING A
 HYDROCARBON-BEARING FORMATION**

BACKGROUND OF THE INVENTION

This invention relates generally to a method of recovering hydrocarbons from unconsolidated formations. More particularly, this invention pertains to a method of consolidating the formation adjacent a production well bore by thermal means.

In the production of hydrocarbons from a subterranean formation, frequently the formation encountered is composed of loosely cemented or unconsolidated sands. This is particularly true in the fields of California, Louisiana and Southern Texas. If precautionary measures are not taken, once the cap rock is penetrated, large quantities of sand may flow to the surface with the oil and/or gas produced from the formation. The presence of sand during production causes equipment damage, particularly in the form of erosion, and in severe cases, may even cause collapse of the well casing.

Various techniques have been proposed to prevent the production of sand along with the hydrocarbons contained in the formation. Generally, a perforated well casing or a liner having a plurality of holes or slots adjacent the hydrocarbon-bearing stratum is provided to allow the fluids to flow through the openings and into the well bore. Screening and/or gravel packing is provided about the holes or slots to filter and protect against sand intrusion into the well bore. This method, although sometimes quite effective, is both expensive and time consuming, particularly due to the extensive preparation and workovers required.

More recent proposals include consolidation of the formation sands by thermal means. In this method, the unconsolidated sand adjacent the well bore is consolidated by exposing the formation to a temperature in the range of about 700° F. to about 150° F. A coke-like deposit formed by carbonizing in place crude, provides a means for bonding the particles of sand, resulting in a partially rigid structure. The primary shortcoming of this method is that the coke-like material is subject to decomposition particularly upon the further application of elevated temperatures. When practicing in situ combustion as a secondary recovery technique, temperatures may be of a sufficient magnitude to cause decomposition of the coke-like bonding means and thereby unconsolidate the formation. By the method of this invention, a formation may be irreversibly consolidated and provide a rigid structural body while maintaining the desired permeability.

SUMMARY OF THE INVENTION

The invention herein disclosed provides an improved method for consolidating a hydrocarbon-bearing formation. Consolidation of the formation is accomplished by exposure to a temperature sufficiently high to cause incipient fusion of the sand contained therein, thereby creating a rigid and permeable formation.

The primary advantage made possible by the method of this invention is that effective consolidation of a formation is provided. Since the loose or friable sands in the previously unconsolidated formation are fused together, the consolidation of the formation is permanent due to the irreversible process employed. Subsequent exposure of the consolidated formation to elevated temperatures produces no detrimental effects. Further treatment, in accordance with the method of this invention renders a stable formation and maintains adequate permeability therethrough.

Accordingly, it is a primary object of this invention to provide an effective method for consolidating a hydrocarbon-bearing formation.

A further object of this invention is to provide a novel method for irreversibly consolidating a formation and maintaining the permeability thereof.

These and other objects, advantages and features of the invention will become more apparent from the following description taken in conjunction with the accompanying drawing.

BRIEF DESCRIPTION OF THE DRAWING

The drawing depicts an elevation view, partly in cross section, of a well bore penetrating an unconsolidated hydrocarbon-bearing formation and containing a heat generating means therein.

DESCRIPTION OF THE PREFERRED EMBODIMENT

With the method of this invention, unconsolidated hydrocarbon-bearing formations are effectively treated to improve the structural capabilities thereof. Thermal means are utilized to consolidate the formation and thereby eliminate the necessity for screening and/or gravel packing adjacent the well casing. In addition, treatment in accordance with the method of this invention renders the formation capable of producing the hydrocarbons contained therein, since the residual permeability and porosity thereof is maintained or improved.

Referring now to the drawing, which schematically illustrates one embodiment of the practice of this invention, there is shown a well bore 10 penetrating an unconsolidated or loosely packed sand formation indicated at 20. A well casing 11 is positioned within the well bore 10 and is provided with perforations 12 adjacent the unconsolidated hydrocarbon-bearing formation 20.

A suitable heating device is lowered into the well bore 10 and positioned adjacent the perforations 12 in the well casing. The perforations 12 provide a means for communication with the formation to be consolidated. Various types of heating devices are suitable for the method of this invention, some of these including downhole heaters, electrical heating devices, chemical compounds or other combustibles placed into the well bore 10. As illustrated in the drawing, an ignition package 30, as disclosed in the copending, coassigned application for patent of a **METHOD AND APPARATUS FOR INITIATING IN SITU COMBUSTION**, Serial No. 708,915 filed February 28, 1968, the disclosure of which is incorporated herein on this reference thereto, may be utilized. Therein is disclosed, an apparatus which will generate sufficiently high temperatures to carry out the method of this invention. The lower chamber of the ignition package 30 contains a fuel pack 31 and is placed adjacent the stratum to be treated. Inserted in the fuel pack and positioned in a predetermined relationship are a plurality of ignitors 32 which are activated by an electrical signal generated at the surface of the well bore. These ignitors initiate combustion of the fuel pack, preferably a kerosene soaked charcoal material, the combustion thereof being sustained by the injection of a combustion supporting gas into the well bore. Further, the upper chamber of the ignition package 30 contains an additional supply of fuel for replenishing that consumed in the lower chamber, thereby insuring generation of temperatures sufficiently high and within a relatively short period of time necessary for consolidation of the formation adjacent the well bore.

A stand-off or spacing means 33 on the bottom of the ignition package rests on the bottom of the well bore and provides means for positioning the fuel pack 30 adjacent the formation to be treated. If it is desired, the ignition train disclosed in the above referenced application for patent also may be utilized in the consolidation of the hydrocarbon-bearing formation. The injection of a combustible material into the formation, the material preferably having a self-ignition temperature and flash point lower than that of the crude contained in the formation, provides a means for consolidating the formation to a greater extent.

Consolidation of the sand is accomplished by generating sufficiently high temperatures to cause incipient fusion of the sand; thereby creating a solid unitary permeable mass, as shown at 21. In order to fuse the unconsolidated formation, temperatures in excess of about 1800° F. but below the temperature at which glazing of the sand occurs, are preferred. Exposure of the formation to temperatures of this magnitude results in a white, consolidated, porous, rock-like material. Further, the formation is irreversibly consolidated and sub-

sequent exposures to elevated temperatures will not destroy the characteristics thereof. It is noted that this result is different from that disclosed in the prior art, wherein a coke-like material is used to consolidate the formation. In that method, subsequent exposures to elevated temperatures will decompose the coke-like bonding material and destroy the consolidation.

Inspection of a previously unconsolidated sand based formation, treated by the method of this invention, reveals that upon consolidation thereof, the sand became a rigid unitary mass. Permeability measurements of a sample indicated an air permeability, measured by passing nitrogen therethrough, of about 12 darcies. Such a permeability is quite adequate for subsequent production of the hydrocarbons contained in the formation. Treatment of a formation by the thermal means disclosed herein renders the formation suitable for subsequent production of hydrocarbons free from any sands and eliminates the necessity for screening and/or gravel packing about the well casing adjacent the unconsolidated formation. Upon completion of a formation in accordance with means disclosed herein, the hydrocarbons may be produced by means well known in the art. Alternatively, treatment in accordance with the method disclosed herein may be utilized in an injection well followed by the introduction of drive fluid therein, and subsequent production of hydrocarbons through an adjacent production well.

Thus, there has been shown and described an improved method of consolidating a hydrocarbon-bearing formation by thermal means.

Other modifications and variations of the invention as hereinbefore set forth may be made without departing from the spirit and scope thereof, and therefore, only such limitations should be imposed as are indicated in the appended claims.

I claim:

75

5 1. A method of recovering hydrocarbons from an unconsolidated hydrocarbon-bearing formation traversed by a well bore with a heat generating means positioned adjacent said hydrocarbon bearing formation comprising a charcoal fuel pack pre-soaked with a hydrocarbon liquid, which comprises igniting said fuel pack and generating sufficient heat in said well bore by said heat generating means to attain a temperature therein in excess of 1800°F but below a temperature at which sand glazes whereby incipient fusion and consolidation of the formation adjacent said well bore takes place, and subsequently producing hydrocarbons from said formation via said well bore.

10 2. The method of Claim 1 wherein said well bore has a casing with a plurality of perforations adjacent said unconsolidated hydrocarbon-bearing formation and includes the additional step of introducing a combustible material via said well bore into said formation.

15 3. The method of Claim 2 wherein said combustible material has a self-ignition temperature and flash point lower than that of said hydrocarbons contained in said formation.

20 4. The method of Claim 2 wherein said formation is traversed by two or more well bores which includes the additional steps of introducing a drive fluid into said formation via one of said well bores and recovering hydrocarbons from the other of said well bores.

25 5. The method of Claim 1 wherein the combustion in said charcoal fuel pack is sustained by the introduction of a combustion supporting gas via said well bore into said fuel pack.

6. The method of Claim 1 which includes the step of introducing a combustible material via said well bore into said formation wherein said combustible material has a flash point lower than that of said hydrocarbons contained in said formation.
